ATTORNEYS.

UNITED STATES PATENT OFFICE.

JAMES C. NEWLIN, OF HAVERFORD, PENNSYLVANIA.

SHOE TREE.

Application filed October 31, 1921. Serial No. 511,663.

To all whom it may concern:

Be it known that I, JAMES C. NEWLIN, a citizen of the United States, residing in Haverford, in the county of Delaware and 5 State of Pennsylvania, have invented certain new and useful Improvements in Shoe Trees, whereof the following is a specification, reference being had to the accompanying drawings.

10 My invention relates to trees such as employed in maintaining shoes in a stretched condition to preserve their shape and prevent wrinkling of the leather.

The object of my invention is to enable 15 a device useful for the stated purpose to be quickly applied to and withdrawn from a shoe, readily adjusted to shoes of different sizes, and compactly folded so as to require but little space for its accommodation when 20 not in use. This desiderata I aim to secure in a metallic shoe tree which is extremely light in weight, yet strong and durable, and capable of being cheaply and expeditiously manufactured.

25 Other objects and attendant advantages will be readily understood from the detailed description of a typical embodiment of my invention which follows:

In the drawings, Fig. I is an illustration 30 showing the manner in which a tree conveniently embodying my invention is used.

Fig. II is a perspective view, on a larger scale, showing the shoe tree when extended.

Fig. III is a perspective view of the device after folding.

Fig. IV is a longitudinal sectional view 40 of an extensible segment of the tree showing the means whereby the constituent sections of the same are secured in adjusted positions; and

Fig. V is a detail cross sectional view along the line V—V of Fig. IV.

The organization herein represented as typical of my invention comprises a series of 45 segments including a toe piece 1, an extensible intermediate piece 5, and a heel piece 20. The toe piece 1 is preferably made of sheet metal appropriately shaped to conform to the toe of the shoe and has rearwardly extending wings or tabs 2—2 which are pivoted at 3—3 to the end of one of the constituent sections 6 of the intermediate segment 5. The section 6, it will be noted, is of U shaped cross section and within it is 50 telescoped a correspondingly shaped companion section 7. The lower edges of the

larger or outer sections 6 are turned inwardly as at 8—8 in Fig. V, so as to retain the inner section 7.

At its top the segment section 6 has an 60 elongated slot 10, the opposite longitudinal edges of which are notched as at 11—11. To the under face of the top of the section 7 is riveted a locking member in the form of a leaf spring 12 whose free end is first bent 65 perpendicularly to project through an opening 13 in the top of the section 7, and beyond, is reduced in width with production of shoulders 14—14 and curved laterally to afford a thumb tab 15. From Fig. II, it will 70 be noted that the shoulders 14 are normally engaged within the notches 11 at the sides of the slot 10 to hold the sections 6, 7 of the segment 5 against relative displacement. When it is desired to adjust the length of 75 the intermediate segment to adapt the tree to shoes of different sizes, the thumb tab 15 of the spring member 12 is depressed until the shoulders 14 of the latter clear the notches 11, whereupon the section 7 may be 80 shifted to any desired extent within the limits of the slot 10 and subsequently locked by selection of the proper cooperative notches when the desired adjustment has 85

The heel piece 20, as herein shown, is bent from a single piece of strip metal with its ends pivoted at the interior of the section 7 of the segment 5 as clearly shown at 21 in the drawings. At its rear, the heel piece 90 is preferably rounded as at 22 for engagement within the heel of the shoe, and when the tree is not in use, is serviceable as a hanger whereby the structure may be 95 suspended in extended position from a suitable wall peg or hook.

In applying my improved shoe tree, the toe piece 1 is first inserted so as to engage within the tip of the shoe, the tail section 20 then pushed into place within the heel, and the intermediate segment 5 finally depressed. From Fig. I, it will be perceived 100 that the intermediate segment 5 acts after the manner of a toggle by which the toe and heel piece are projected longitudinally to stretch the shoe to the requisite extent predetermined by the adjustment of said segment as already understood.

In folding the structure, the heel piece 20 is turned under and into the intermediate 110 segment 5 and the latter subsequently swung into the hollow of the toe piece 1 as illus-

trated in Fig. III of the drawings. When thus folded, the shoe tree is not only free from objectionable protuberances or projections, but in such compact form as to be capable of accommodation in a very small space. By virtue of this capacity, the tree is especially adapted to the use of travelers. Moreover, by reason of being made wholly of sheet metal, the tree is rendered light in weight, yet strong, sturdy and durable, and may be readily constructed at an extremely low cost, from die stampings.

Having thus described my invention, I claim:

1. A shoe tree constructed of sheet metal stampings, comprising a hollow toe piece having its inner end formed with inset spaced terminal extensions thereafter, an intermediate section comprising a pair of interfiting channel members, one end of one member being received between the terminal extension thereafter of the toe piece in pivotal relation, a heel piece pivoted to the remote end of the other section and means to hold said sections against relative movement subsequent to adjustment.

2. A shoe tree constructed of sheet metal stampings comprising a hollow toe piece having its inner end formed with spaced terminals, an intermediate section comprising a pair of interfiting channel members, one end of one member being received between the terminals of the toe piece in pivotal relation, a U-shaped heel piece having its terminals pivoted to the remote end of the other section, and means to hold said sections against relative movement subsequent to adjustment.

3. A shoe tree comprising a toe piece, a heel piece and an intermediate connecting member comprising a pair of interfiting channel members one of which is provided with a single opening, and the other having a registering longitudinal slot, the edges of which are serrated to form opposed pairs of notches, and a spring finger having one end secured to the inner side of the first section and its other end extending through the opening thereof and the slot of the second section and reduced to provide shoulders to enter the notches and hold the members against relative movement, and to permit relative movement thereof when the spring finger is depressed to withdraw the shoulders from the notches.

4. A shoe tree comprising an open sided, sheet metal toe piece, an open sided intermediate segment pivoted to the toe piece for relative movement and adapted to be folded into the toe piece with the open sides of the latter and the segment in opposed relation, and a heel piece pivoted to the segment and constructed and arranged to be folded into and enclosed within the segment.

5. A shoe tree comprising an open sided, sheet metal toe piece, an intermediate segment composed of channel sections in nested relation and adapted to be folded into the toe piece with the open side of the latter and the open sides of the channel sections in opposed relation, a heel piece pivoted to one of the channel sections, and foldable into and constructed and arranged so as to be enclosed by the channel sections, and an adjustable means for locking the channel sections against relative movement.

6. A shoe tree composed of sheet metal stampings and comprising a toe piece, an intermediate channel member pivoted thereto, and a U-shaped heel piece having its terminals pivoted to the inner sides of the channel member and constructed and arranged to be folded and enclosed within the sides of said channel member.

7. In a shoe tree, a toe piece in the form of a stamping fabricated from an integral piece of sheet material and conforming to the shape of the toe of the shoe, and having a flange formed around the edge of the toe piece constituting a partial sole portion and to add rigidity to the structure, a pair of apertured ears formed integrally with the side portions of the toe piece and bent toward each other to dispose them in closely spaced relation, said partial sole portion and said ears being integrally connected, an intermediate telescopic channel section member pivoted at one end between the apertured ears and a U-shaped heel piece pivoted to the remote end of said telescopic member, and means for securing the telescopic member sections in adjusted relation.

In testimony whereof, I have hereunto signed my name at Philadelphia, Pennsylvania, this 26th day of October, 1921.

JAMES C. NEWLIN.
